UNITED STATES PATENT OFFICE.

HENRY DENLINGER, OF PORTLAND, OREGON.

INDEX.

No. 878,612.

Specification of Letters Patent.

Patented Feb. 11, 1908.

Application filed October 31, 1905. Serial No. 285,284.

To all whom it may concern:

Be it known that I, HENRY DENLINGER, a citizen of the United States, residing in Portland, in the county of Multnomah and State of Oregon, have invented certain new and useful Improvements in an Index, of which the following is a specification.

This invention relates to an index, and more particularly to an index for a file envelop or record card.

Among the salient objects of the invention are to provide an index for a filing envelop, record card or the like, whereby any particular envelop or card of a group or collection is designated by its appearance while in place in the group and can be readily selected at a glance without the necessity of handling or fingering the others of the group; to provide an index for envelops or cards whereby the initial letter (or letters) of a name or the initial or initials of a person are indicated upon the exposed portion, preferably the edge, of the envelop or card, thus making it possible to select from a collection thereof, at a glance, by means of exposed, but not projecting, indications, the envelop or card containing the documents or record for any given name; to provide an index wherein certain lines thereof will indicate certain letters, as for example, the vowels; to provide an index of the character referred to which shall be free from projecting tabs or tongues and the accompanying objections thereto; and in general, to provide an index which is simple, practicable, expeditious and economical.

To the above ends the invention consists in the matters hereinafter set forth and will be readily understood from the following description, reference being had to the accompanying sheets of drawings in which—

Figure 1 is a face view of an envelop or card provided with an index of the character referred to; Fig. 2 is a top edge view of the same; Fig. 3 is a view showing a collection of the envelops or cards grouped together in a box or drawer, the upper edges thereof being exposed and carrying the indicating marks or designations; and Fig. 4 is a similar view showing the method more fully extended.

Referring to the drawings, 1 designates an envelop or card provided upon the side and near one edge thereof with a series of short lines 2 dividing it into a series of spaces 3. In these spaces the letters of the alphabet are arranged, as clearly indicated on Fig. 1.

The short lines 2 are extended over the edge of the envelop or card and give a lined effect, as at 4, when a group of the envelops are placed in a drawer or filing box, as will be readily understood by reference to Fig. 3. By this arrangement like letters on different cards are in alinement with each other.

In order to designate certain letters of the alphabet, as for example, the vowels, the lines on each side of the spaces or divisions containing these letters may be more heavily ruled, or may be of different colors, as will be understood by reference to the drawings, Fig. 4.

In arranging the envelop or card for use, the name of the person whose business is to be kept therein or thereon is written upon the face of the envelop or card, preferably so that the initial letter of his surname comes in alinement with the corresponding letter on the alphabet, as arranged in the spaces along the upper edge of the envelop. For example, if the man's name is J. F. Argo, Argo should be written so that the "A" or initial letter thereof would be in alinement with the "a" division upon the envelop or card and the initials following it, as clearly indicated on Fig. 1.

In order that the envelop or card may be made to indicate by its edge appearance the initial letter of the name written thereupon, the edge of the card at the "a" section or division is shaded by some suitable coloring or staining substance, the shading extending downwardly over the side thereof a short distance, as indicated at 5, Fig. 1, the edge of the shaded portion being seen at 5, Fig. 2. Thus it will be understood that this envelop contains a name commencing with "A", no matter at what place in the box it may be, and if it is out of place or away from the group of "a" cards or envelops in the front of the box, it will be detected at a glance and put into its proper place at the front of the box or drawer. The second letter of the name (r) can be indicated by a similar shading in the middle of the "r" division on the envelop or card, but not extending fully across the space, as indicated at 6, Figs. 1 and 2. This shading should be of another color so as to be readily recognized.

The initials of the person (J. F.) are designated by short shaded portions, but instead of being placed in the middle of the space or division in which is the letter of the alphabet,

the shaded portion which indicates the initial is placed at the side of the section or division, the shading for the first initial being placed at the side of its space nearest or towards the name-indicating space (a), and the shading for the second initial at the side of its space farthest removed from the name-indicating space, as indicated at 7 and 8, respectively, Fig. 1. The shading in the spaces for indicating the initials should be of different colors and different from that used to indicate the initial letter or letters of the name. Likewise the lines which separate the spaces about the vowels, or other special letters, should be heavier or of a different color from the rest of the space lines to break up the sameness.

As a matter of convenience and to assist in more readily picking out the initials and the initial letter of the surname, groups of colors might be selected for the shading, as, for example, red, white and blue. The shaded portion for the space which indicates the name on the envelop might be a light blue, so that it would take another color upon or over it with proper contrast in case one initial should happen to be the same as the initial letter of the surname. The short shaded portion for the first initial could be made in red, and that for the second initial, in white. Thus, if these colors were applied to the name J. F. Argo, used to illustrate the invention, the red would indicate the J, white the F, and blue the initial letter of the surname "A", and if it was desired to also indicate the second letter of the surname (r), that could be done by using still another color for shading the middle portion only of the "r" division. If one of the initials should also be "A", it would be indicated by placing the coloring for that initial over the blue shading which indicates the initial letter of the surname, the contrast being sufficiently distinct to clearly indicate the initial. It will be seen that the shading of the letters makes it possible to select the envelop or card wanted by the appearance of the exposed edges.

It will be understood that where a number of "a" cards come together, there will be an extended shaded portion in the "a" division, and so with the other letters, whether they be second or third letters in the surname, or the initials of the name, providing, of course, a group of names have the same second or third letters, or the same initials. Where there are a great many in the group indicating the initial letter of the surname (see Fig. 4, "a") the name might be selected from the second letter thereof, or by the third letter, these being shaded with different colors and to the side. Thus, where there are many "a's", "r" being the second letter, a glance down the "r" column opposite the "a" group would single out the

one wanted. It will be seen, therefore, that it is not necessary to use the principal or main group only, but that the name can be selected by the sub-groups, as by second, third, or initial letters.

By reference to Fig. 4, in selecting the name used to illustrate the invention, the person looking for the envelop containing J. F. Argo's documents, would naturally glance down the "A" division, at the same time, running his eye down the row indicating the "J" row, which would indicate that of the "A" cards or envelops it must be one which is opposite the "J" shading, thus reducing the number of cards, one of which it must be, and by a further glance, he sees that it must be one of the cards which is shaded at the "F" division. Thus by carrying the initial letter of the surname and the initials in mind as he runs his hand over the columns he naturally puts his hand upon the card or envelop wanted. If the card is out of place, it is more easily detected than ever.

The shading can be done in a variety of ways, as with some simple coloring or staining substance, or by pasting a thin piece of adhesive fabric of the proper color over the edge of the envelop or card so that it fits closely and does not protrude or hang loose.

The index here described is inexpensive and practicable and capable of indefinite use. It does away with the projecting tabs and tongues which are always being broken off and which do not permit of such ready or extended application.

While I have described the invention as applied in the manner shown in the drawings, it is obvious that modifications can be made without departing from the spirit of the invention and I do not limit the invention to the particular form shown and described.

I claim as my invention:

1. A card or envelop provided with the letters of the alphabet and with one or more differentiated indicating marks so associated with the letters of said alphabet as to indicate in their order the first or initial letters of the name thereupon.

2. A set of cards or envelops provided with a series of division marks subdividing them into spaces and also provided with the letters of the alphabet, and with one or more indicating marks so positioned within said spaces as to indicate in their order the first or initial letters of the name associated therewith, substantially as described.

3. A card or envelop provided with a series of division marks subdividing a portion thereof into spaces and with the letters of the alphabet distributed within said spaces, and with one or more differentiated indicating marks distributed among said spaces to designate in their order the initial letters of the name thereon, substantially as described.

4. A filing envelop provided upon its face

near its upper edge with a series of marks dividing it into spaces, some of said marks being differentiated to particularly designate certain letters of the alphabet distributed in said spaces upon said envelop, and with one or more colored indicating marks within said spaces and associated with the

letters of the alphabet which are the first or initial letters of the name upon said envelop, substantially as described.
